FOAM GENERATING DEVICES

Harold G. Strohm, Waukegan, Ill., assignor to Production Specialists, West Allis, Wis., a partnership of Wisconsin

Filed Mar. 31, 1958, Ser. No. 725,288

2 Claims. (Cl. 261—76)

This invention relates generally to foam generating devices, and while not limited thereto, relates more particularly to devices for generating foam for use as a coolant in metal machining processes.

Intense heat generated by friction in metal machining requires that commercial coolant, various types of oil, or other liquids be employed to prolong tool life and to prevent damage to the material being worked. Formerly, a mist, a continuous flood or a solid stream of coolant was directed onto the tool and the material. It has been discovered, however, that use of coolants in a foamy state produces more satisfactory results in that splashing is substantially eliminated, additional surface area of tool and material is covered by the foam which tends to cling, and more efficient cooling is effected since a larger quantity of coolant can be applied and is retained for a given period. Some existing types of foam generating devices have proven unsatisfactory because they are relatively complicated in construction, employ screens or a number of moving parts, are extremely susceptible to clogging with metal chips and other foreign matter, or require the use of compressed air or other gases in conjunction with a liquid coolant to achieve foaming action. It is desirable, therefore, to have a foam generating device which overcomes the aforementioned and other difficulties and has numerous other advantages.

Accordingly, it is an object of this invention to provide an improved foam generating device for liquid coolants which does not employ screens, moving parts, or compressed gases to obtain foaming action.

Another object is to provide a device of the aforesaid character which is relatively simple to construct, employs a minimum number of constituent elements, is extremely reliable in use, can be readily cleaned, can be economically produced, is durable, and is readily adaptable to a wide variety of applications.

Other objects and advantages of the invention will hereinafter become apparent.

The accompanying drawing illustrates one embodiment of the invention which will hereinafter be described, it being understood that the embodiment illustrated is susceptible of various modifications with respect to details thereof without departing from the scope of the appended claims.

In the drawing:

Figure 1 is a cross sectional view, actual size, of a foam generating device embodying the invention taken along line 1—1 of Fig. 2;

Fig. 2 is a top plan view of the device showing certain details thereof; and

Fig. 3 is an elevational view in reduced scale of the device shown in Figs. 1 and 2 illustrating the manner in which it is employed with appropriate inlet and outlet piping.

Referring generally to Figs. 1, 2 and 3, the reference numeral 10 designates a foam generating device incorporating the invention. The foam generating device 10 comprises a generally cylindrical hollow shell member 11

which has its lower end closed by an integrally formed bottom wall 12 and which has its upper end enclosed by a cover member 13 which is rigidly secured to the shell 11. Shell 11 and cover 13 are preferably formed by molding from some type of plastic material which is not adversely affected by chemical substances employed in some commercial coolants, but obviously, metal or other suitable materials may be utilized instead.

Referring specifically to Fig. 1, it is seen that the bottom wall 12 of shell 11 is provided with an integrally formed substantially cylindrical hollow stem portion 14 which extends upwardly for some distance into the chamber 15 of the shell. The wall of the stem 14 is arranged with respect to the wall of the shell 11 so as to form a moat 16 therebetween. Stem portion 14 is provided with a bore 17 which communicates with chamber 15 and the bore is threaded and adapted to accommodate the externally threaded end of a discharge pipe or nozzle 25, as Fig. 3 makes clear.

Referring to Figs. 1 and 2, it is seen that cover member 13, which has a substantially circular peripheral contour, is provided with an annular groove or shoulder 18 around its lower outer edge which adapts it to fit snugly within the open upper end of shell 11. Three rivets or pins 19a, 19b and 19c extend through the wall of shell 11 and into the cover to rigidly secure the latter to the shell.

Cover member 13 has a central portion 20 which is substantially thicker than the remainder thereof and which depends into chamber 15. A relatively large threaded

recess or opening 21 extends into but not through portion 20 and is adapted to accommodate the externally threaded end of an inlet pipe 22, as Fig. 3 makes clear. The bottom wall or floor 23 of portion 20 is provided with four orifices 23a, 23b, 23c and 23d which extend therethrough and communicate with chamber 15. Preferably, the orifices 23a, 23b, 23c and 23d are arranged in a circle about the center point of floor 23 of portion 20 and are spaced an angular distance of ninety degrees from each other, as Fig. 2 makes clear. Each orifices 23a, 23b,

23c and 23d, which has a substantially circular cross section, is disposed so that the axis thereof, if extended downwardly into chamber 15, would pass through a point located substantially at the intersection of the inner wall surface of the shell 11 and the inner surface of the chamber floor 23, as Fig. 1 shows. Cover member 13 is also provided with four orifices 24a, 24b, 24c and 24d which extend therethrough and which communicate with chamber 15 and which are arranged with respect to each other as shown in Fig. 2.

50 The invention operates in the following manner:

Assume that inlet pipe 22 and outlet pipe 25 are connected to device 10 as shown in Fig. 3 and that the device is in the substantially upright position shown therein. Further assume that a suitable liquid coolant is being forced or pumped under pressure, which, for example should be greater than eight pounds per square inch, through pipe 22 from a source (not shown) toward device 10. The coolant entering recess 21 is forced through the orifices 23a, 23b, 23c and 23d and is thus broken into four solid jet streams of relatively high velocity. Each of the four streams is aimed toward the junction of the inner surfaces of the side and bottom wall 12 of shell 11. As each solid stream impinges against the interior surface of the shell 11 at the said junction point, it loses its character as a solid stream and is forced to swirl back upon itself. Some of the coolant swirls up the side wall of shell 11 for a short distance and some is forced across the bottom wall 12. This localized turbulent activity effects transformation of the coolant from its former liquid state into a foaming or bubbly coherent mass. Foam accumulates in moat 16 and when its level reaches the height of stem 14 it spills over the edge of

the latter into opening 17 and from thence into discharge nozzle 25 from whence it can be directed as desired.

Preferably, the rate at which coolant is introduced into device 10 should be such that moat 16 is filled to overflowing with coolant in the foamy state. However, should coolant be introduced too rapidly with respect to the capacity of moat 16 or the capacity of opening 17 to carry it away, the moat tends to fill with coolant in its liquid state and the foaming action is defeated.

The orifices 24a, 24b, 24c and 24d in cover 13 permit the ingress and egress of air into chamber 15 while foam is being generated and should be sufficiently large to prevent reduction of air pressure of formation of a partial vacuum within chamber 14 as coolant flows through device 10 which would tend to inhibit or interfere with the smooth and constant flow of foam from opening 17. Reduced air pressure within chamber 15 tends to cause air to be drawn up through discharge opening 17.

It will be apparent to those skilled in the art that although device 10 has been shown as comprised of the shell member 11 and the cover member 13, the device could be manufactured as an integral unit.

I claim:

1. In combination, a hollow cylindrical member, a top portion enclosing the top end of said member, said top portion being adapted for connection to the discharge end of a tube supplying liquid under pressure, said top portion being provided with a plurality of angularly disposed apertures for directing said fluid into said hollow cylindrical member and toward the side and bottom thereof in jet streams, means comprising at least one aperture for permitting egress and ingress of air into said hollow cylindrical member, a bottom portion enclosing the bottom end of said member, said bottom portion being provided with a centrally disposed aperture, and a projection

surrounding said centrally disposed aperture inside of said cylindrical member to provide a moat between said centrally disposed aperture and the side of said cylindrical member, said moat being adapted to retain a quantity of liquid therein, whereby said jet streams play upon said liquid in said moat to break it into foam, said foam being momentarily contained in said moat before spilling over into the said centrally disposed aperture.

2. A device for generating foam comprising an enclosed 10 chamber having side and bottom walls, at least one air port communicating with the upper portion of said chamber, for the ingress and egress of air, at least one opening through said bottom wall of said chamber, means disposed about said opening to form a moat between 15 said opening and said side wall, said moat being adapted to retain a substantial quantity of liquid before said liquid reaches the top level of said means, and means associated with the upper portion of said chamber and adapted for connection with the discharge end of a tube containing 20 liquid under pressure to form said liquid into jet streams of relatively high velocity, said last recited means comprising a member provided with a plurality of holes of relatively small diameter adapted to direct said streams toward a line formed by the intersection of the inner surfaces 25 of said side and bottom walls of said container.
